SPARK PLUG

Joseph P. Kletz, Chicago, Ill.

Application February 17, 1939, Serial No. 257,001

4 Claims. (Cl. 123—169)

The invention relates to a spark plug and more especially to an air and liquid cooled spark plug with electrical replacement parts.

The primary object of the invention is the provision of a spark plug of this character, wherein the main body or shell and the insulator associated therewith is externally finned to assure, in the operation of the plug, the cooling thereof, while the electrical parts of said plug are readily separable from each other for replacement purposes.

Another object of the invention is the provision of a spark plug of this character, wherein one of the electrodes is fitted thereto in a novel manner 15 to regulate its association with the other electrode for proper spark gapping of the same.

A further object of the invention is the provision of a spark plug of this character, wherein the parts are assembled in a unique manner, giving 20 longevity to the plug and minimizing breakage as well as enabling replacement of said parts with dispatch.

A still further object of the invention is the provision of a spark plug of this character, which 25 is simple in its construction, thoroughly reliable and efficient in operation, easy of repairs, strong, durable, and inexpensive to manufacture.

With these and other objects in view, the invention consists in the features of construction, 30 combination and arrangement of parts as will be hereinafter more fully described, illustrated in the accompanying drawing, which discloses the preferred embodiment of the invention and pointed out in the claims hereunto appended.

35 In the accompanying drawing:

Figure 1 is an elevation of a spark plug constructed in accordance with the invention.

Figure 2 is a vertical longitudinal sectional view thereof.

40 Figure 3 is a bottom plan view.

Similar reference characters indicate corresponding parts throughout the several views in the drawing.

Referring to the drawing in detail, the spark 45 plug constructed in accordance with the invention comprises a body 10 constituting the metal shell having an externally threaded annular skirt end for the creation of a nipple 11 so that this body can be associated with an internal combustion engine and arranged in the ignition system of a motor vehicle, as usual, being preferably tapped into a hole for the plug in the head of the block of such engine. The body 10 uppermost with relation to the skirted end 11 is externally 50 peripherally finned at 12 and these fins are

square-faced, as at 13, so that the body 10 can be screwed into its seating conveniently. The fins are spaced from each other in a vertical direction.

Internally of the body 10 is a circular ledge 14 forming a shoulder or seat for an insulator 15 of tubular construction, having the lower downwardly tapered inner end 16, while the uppermost portion of this insulator is of approximately uniform circular contour in cross section and said portion carries externally thereof annular fins 17, these being vertically spaced from each other, as is shown in Figures 1 and 2 of the drawing.

The insulator 15 is held seated by a nut 18 having a center clearance for the said insulator 15 and is separably threaded into the upper end of the body 10. The nut 18, as usual, is flat-faced for wrench engagement therewith so that it can be separably fastened in the body. The insulator has associated therewith suitable gaskets 19 20 and 20, respectively.

Fitted centrally in the insulator 15 is the main electrode 21 while built at the edge of the skirt end 11 is a boss 22. This boss has fitted therein a set screw 23 engageable with an auxiliary electrode 24, being slidably fitted in inwardly sloping relation to the main electrode 21 in a guideway 25 formed in said skirt end 11 of the body 10. The adjustment of the electrode 24 with respect to the electrode 21 regulates the sparking gap. The 30 way 25 is squared correspondingly to the squared cross sectional form of the auxiliary electrode 24.

The main electrode 21 is held fitted in the insulator 15 by a nut 26 seating a cap 27 which surrounds said electrode and engages with the 35 uppermost end of the insulator 15.

It is preferable that the main electrode 21 be squared in cross section for a distance thereof and this portion is seated in a correspondingly shaped clearance, thus holding the said electrode 40 against rotation in the insulator 15. The set screw 23 is accessible when the plug has been removed or detached from the engine so that accuracy may be assured in the spark gapping 45 of the said electrodes 21 and 24.

By reason of the construction of the spark plug, the electrical and other parts thereof are susceptible of convenient replacement as the occasion may require.

The cap 27 in association with the main electrode 21 and also the nut 26 enables electrical connection of the plug with the ignition system of the motor.

The tapered end 16 of the insulator 15 ex- 55

tends within the hollow center 28 of the body 10, as shown in Figure 2 of the drawing.

The sparking lower end of the main electrode 24 is preferably squared in cross section and in conformity with the squared cross sectional formation of the auxiliary electrode 24.

What is claimed is:

10. 1. A spark plug of the kind described comprising an externally finned plug body having a skirt portion threaded exteriorly for a portion of its length, a thickened extension on the skirt at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body.
15. 2. A spark plug of the kind described comprising an externally finned plug body having a skirt portion threaded exteriorly for a portion of its length, a thickened extension on the skirt at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body.
20. 3. A spark plug of the kind described comprising an externally finned plug body having a skirt portion threaded exteriorly for a portion of its length, a thickened extension on the skirt at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body, and a locking nut threaded in the outer end of said plug body for removably fastening the insulator interfitted with said body, and a metal cap removably fitting the outer end of the main electrode and seated upon the outer end of said insulator.
25. 4. A spark plug of the kind described comprising an externally finned plug body having a skirt portion threaded exteriorly for a portion of its length, a thickened extension on the skirt at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body, and a locking nut threaded in the outer end of said plug body for removably fastening the insulator interfitted with said body, and a metal cap removably fitting the outer end of the main electrode and seated upon the outer end of said insulator, the main electrode being of a size and cross section considerably less than the interior cross sectional area of said insulator and an internal seating shoulder formed in said plug body of the said insulator.

at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body, and a locking nut threaded in the outer end of said plug body for removably fastening the insulator interfitted with said body, and a metal cap removably fitting the outer end of the main electrode and seated upon the outer end of said insulator.

4. A spark plug of the kind described comprising an externally finned plug body having a skirt portion threaded exteriorly for a portion of its length, a thickened extension on the skirt at one side thereof below the threads and having an inwardly sloping aperture extending diagonally downwardly therethrough, a tubiform insulator interfitting the said plug body and having external annular fins above said body, a main electrode arranged centrally of said insulator and protruding into the plug body, a second electrode slidably fitting the aperture in the thickened extension for adjustment toward and away from the main electrode, means engaged in said thickened extension for fastening the second electrode in adjusted position and accessible at the inner end of the plug body, and a locking nut threaded in the outer end of said plug body for removably fastening the insulator interfitted with said body, and a metal cap removably fitting the outer end of the main electrode and seated upon the outer end of said insulator, the main electrode being of a size and cross section considerably less than the interior cross sectional area of said insulator and an internal seating shoulder formed in said plug body of the said insulator.

JOSEPH P. KLETZ.
